HOSE REEL

Francis A. Nason, Cleveland, Ohio, assignor, by
mesne assignments, to The Lubri-Zol Corporation,
Cleveland, Ohio, a corporation of Ohio

Application June 8, 1932, Serial No. 615,996

6 Claims. (Cl. 242—86)

This invention relates as indicated to hose reels and has specific reference to a form of construction adapted to have wound thereon a flexible conduit for fluid, either liquid or gaseous, in a manner so that the fluid supply will be uninterrupted either by virtue of or during rotation of the reel as such flexible conduit is wound or unwound thereon. It is a further object of my invention to provide an apparatus of the character described in which the reel may be caused to automatically rewind the hose thereon when such hose or like flexible conduit is no longer needed. It is a further object of my invention to provide a hose reel of the character described in which the retractile effect of the reel may be arrested at points of retraction of the hose so that the hose may be employed without having the reel tension exerted thereon. It is a further object of my invention to provide a structure of the character described which shall be extremely light and yet durable to withstand the rough usage to which apparatus of this character is usually subjected. Other objects of my invention will appear as the description proceeds.

To the accomplishment of the foregoing and related ends, said invention then consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

35 In said annexed drawing:

Figure 1 is a side elevational view of a hose reel constructed in accordance with the principles of my invention; Figure 2 is a transverse, part sectional, part end elevational view of the apparatus illustrated in Figure 1, taken on a plane substantially indicated by the line 2—2; Figure 3 is a fragmentary, part sectional, part side elevational view of the apparatus, as illustrated in Figure 2, taken on a plane substantially indicated by the line 3—3; and Figure 4 is a fragmentary, part sectional, part elevational view of a portion of the apparatus illustrated in Figure 1, taken on a plane substantially indicated by the line 4—4.

50 Referring now more specifically to the drawing and more especially to Figures 1 and 2, the hose reel comprising my invention includes a base frame, generally indicated at 1, which has upwardly projecting laterally spaced standards 2

with the base although any usual method may be employed for fabricating this base structure of the reel.

The standards 2 and 3, at their upper ends, rotatably support an axle 4, the construction of which will be presently given in greater detail.

Secured to the axle 4 and rotatable therewith is a spider 6 and a peripheral hose or flexible conduit receiving flanged portion, generally indicated at 7, which, as most clearly illustrated in Figure 2, is formed of axially spaced flanges 8 and 9.

One end 10 of the axle 4 extending through the supporting bearing on the upper end of the standard 3 is hollow and in communication with a conduit 11 to which the inner end 12 of the hose 13 is secured. The outer end 14 of the hose 13 passes through a bracket 15, which is provided with a plurality of rollers 16 which permit the hose to move through such bracket without subjecting the same to undue wear. The end of the hose carries a stop member 17 resiliently supported by a spring 18 on a nut 19 threaded onto the nipple 20 on the end of the hose. A guide bar 21 is provided to insure that the hose will properly run into the space between the flanges 8 and 9 of the reel as the reel is rotated to wind the hose thereon.

Fluid, either liquid or gaseous, may be continuously supplied under pressure to the hose by means of a swivel coupling, generally indicated at 22, which connects a supply conduit 23 to the hollow terminal 10 of the axle 4. The specific construction of this swivel coupling forms no part of this invention and hence, has not been illustrated in detail and accordingly, will not be further described.

The supporting frame for the reel, more specifically, the standard 2, carries a spring casing, generally indicated at 24, which encloses a clock spring which has its outer end secured to such casing or associated structure and its inner end secured to the hub 5 of the reel and is under sufficient tension so as to, at all times, urge the reel in a counter-clockwise direction, as viewed in Figure 1 and with sufficient force to wind the hose thereon and maintain the stop 17 in engagement with the bracket 15.

In order to lock the reel against rotation while the hose is in use and after predetermined lengths of such hose have been withdrawn from the reel, so that the hose will not be under tension and interfere with its use, I provide a latch construction of unusual simplicity and extreme durability, the form of construction of which will now be explained.

The bearing member associated with the standard 3 or more specifically, the upper end of such standard, has rigidly secured thereto a cam block 25 which, as most clearly illustrated in Figures 1 and 3, is substantially circular in form and provided with a cut-away portion so as to provide a shoulder 26 lying substantially on a horizontal plane on the right side of such cam block as viewed in these figures.

10 The spider or reel proper and more specifically, one of the spokes 6 thereof, has rotatably mounted thereon a latch member 27. In order to reinforce the spoke carrying the latch 27 and in addition, to provide a rigid abutment for the latch when in its engaged position, a brace member 28 extends chordal-wise between the spoke 6 carrying the latch and the inner periphery of the reel body. This brace member is provided with a laterally projecting abutment 29, as most clearly illustrated in Figure 4, on which the rear face 30 of the latch 27 is adapted to seat.

The operation of this latch may be briefly described by having reference to Figures 1, 3 and 4. Assuming that the latch occupies the position illustrated in Figure 1 and it is desired to withdraw the hose 13 for a distance sufficient to reach the point of use, as the hose is withdrawn, the reel will be rotated in a clockwise direction and the latch 27 carried therewith. After the reel 30 has rotated through a central angle of approximately 90°, the latch will have dropped to the position illustrated in Figure 3. A further withdrawal of the hose effecting a further clockwise rotation of the reel will cause the latch 27 to be 35 also rotated about the axis of the reel. As the latch 27 moves to the position which may be termed ten o'clock on Figure 3, the rear face 30 of the latch will ride on the outer periphery of the cam 25 and will continue to ride on the cam 40 until the spoke carrying the latch moves to the three o'clock position illustrated in Figure 3, whereupon, the latch will drop behind the projection 26 and occupy the position illustrated in Figure 1. The tension on the hose can then be 45 relieved and the latch will prevent the clock-spring from tending to wind up the reel so that the hose may be used without having any tension exerted thereon. It is to be noted, of course, that the reel might be rotated for a further complete 50 revolution, whereupon the operation of the latch would be, as above described, to hold the reel in this further rotated position.

After the reel has become latched in the above defined manner, in order to unlatch the same 55 and permit the spring to again wind up the hose, it is only necessary that the hose be further withdrawn to effect a clockwise rotation of the spoke carrying the latch from the three o'clock to approximately the six o'clock position, as viewed in 60 Figures 1 and 3, whereupon, the latch will drop to the position illustrated in Figure 3 so that the tension on the hose may be relieved and the spring permitted to rotate the reel in a counter-clockwise direction and during such rotation, the latch will 65 not interfere with the winding of the reel.

From the above description of the construction and operation of the latch, it will be apparent that the same is very simple and effective in its operation and constructed in a manner so that 70 the latch may carry the stress to which it is subjected without the possibility of failure of itself or any of the associated parts.

The above described form of reel construction will preferably have incorporated therein a com- 75 mon form of centrifugal brake which has not

been illustrated in the drawing but which will prevent the spring from rewinding the hose at a too rapid rate which might result in the destruction or excessive wear of the hose or parts of the reel.

As most clearly illustrated in Figure 2, the cam block 25 is held against rotation by a bolt 25a which passes through the standard 3 and terminally thereably engages a threaded aperture in the cam block. As most clearly illustrated in Figure 1, the cam block 25 is provided with two other circumferentially spaced threaded apertures 25' and 25'', so that by means of the bolt 25a the cam block may be secured to the stand in any one of three selected positions. This provision is made so that the cam block may be supported in proper position with the notch 26 on a horizontal plane whether the stand 1 be secured to a flat horizontal plane, a vertical plane or the under side of the horizontal plane such as a 20 ceiling.

Other modes of applying the principle of my invention may be employed instead of the one explained, change being made as regards the mechanism herein disclosed, provided the means stated 25 by any of the following claims or the equivalent of such stated means be employed.

I therefore particularly point out and distinctly claim as my invention:

1. In a winding device, a reel having a grooved 30 rim, an axial support for said reel, means for constantly urging the reel in winding direction, a latch pivotally mounted on the side of the reel, a fixed abutment adapted to be engaged by said latch to prevent winding rotation of the reel, 35 and an abutment on said reel adjacent to said latch, said latter abutment adapted to control the engagement of the latch with the fixed abutment, whereby rewinding movement of the reel may be arrested following each engagement of 40 the latch with the fixed abutment after unwinding movement of the reel of less than a quarter of a revolution or slightly more than a full revolution.

2. In a winding device, a reel having a grooved 45 rim, an axial support for said reel, automatic wheel rotating means for constantly urging the wheel in winding direction, a latch pivotally mounted on the side of the reel, a fixed abutment disposed in a horizontal plane adapted to be engaged by the pivoted latch, an abutment shoulder formed chordwise on the reel just below the latch 50 adapted to support the latch for engagement of the latch with the fixed abutment, whereby upon an approximate quarter turn of the reel in unwinding direction the latch will be dislodged from the abutment on the reel and will depend downwardly under the force of gravity, winding rotation thereupon disposing the latch in outwardly 55 extended position on the abutment of the reel 60 for clearing the fixed abutment.

3. In a winding device, a reel, an axial support for said reel, automatic wheel rotating means for constantly urging the wheel in winding direction, a latch pivotally mounted on the reel, a fixed abutment disposed in a horizontal plane adapted 65 to be engaged by the pivoted latch, an abutment shoulder formed on the reel adapted to support the latch at the time of engagement of the latch with the fixed abutment, whereby upon a quarter 70 turn of the reel in unwinding direction the latch will be dislodged from the abutment on the reel and will depend downwardly under the action of gravity, winding rotation thereupon engaging the latch on the abutment of the reel in outwardly 75

- extended position for clearing the fixed abutment.
4. In a hose reel, the combination with a rotatable hose carrying wheel, a supporting member therefor and means interconnecting said wheel and support whereby the former is constantly urged for rotation in a winding direction, of locking means including a locking member supported on said wheel for limited movement relative thereto under the influence of gravity upon rotation of said wheel, means carried by said support adjacent said movable locking member and adapted to be engaged thereby and locked, and an abutment means on said wheel adjacent said movable member adapted to so restrict the movement of the latter relatively to the wheel that winding rotation at any speed of said wheel from certain of its angular positions relative to said support will be unopposed but arrested by said locking means within less than one revolution from other angular positions of said wheel.
5. In a hose reel, the combination with a rotatable hose carrying wheel, a supporting member therefor and means interconnecting said wheel, and support whereby the former is constantly urged for rotation in a winding direction, of locking means including a pawl supported on
- said wheel for limited rotation relative thereto under the influence of gravity upon rotation of said wheel, a cam carried by said support adjacent said pawl, an abutment on said wheel adjacent said pawl and arranged to support said pawl against rotation relative to said wheel in one direction when said pawl is in locking engagement with said cam.
6. In a hose reel, the combination with a rotatable hose carrying wheel, a supporting member therefor and means interconnecting said wheel and support whereby the former is constantly urged for rotation in a winding direction, of locking means including a pawl supported on said wheel for limited rotation relative thereto under the influence of gravity upon rotation of said wheel, an abutment on said wheel adjacent said pawl and a cam carried by said support adjacent said pawl, said abutment arranged to hold said pawl in engagement with said cam while said pawl is in locking engagement with said cam, whereby winding rotation at any speed of said wheel from certain of its positions relative to said support will be unopposed but arrested by said pawl within less than one revolution from other positions.

FRANCIS A. NASON.
